M. K. BOWMAN

APPARATUS FOR CLEANING BOILER TUBES

Filed Oct. 21, 1920

Inventor

Mark K. Bowman

By his Attorney

George C. Blaine

UNITED STATES PATENT OFFICE.

MARK K. BOWMAN, OF MONTCLAIR, NEW JERSEY, ASSIGNOR, BY MESNE ASSIGNMENTS, TO RICHARD L. SUYDAM, OF NEW YORK, N. Y.

APPARATUS FOR CLEANING BOILER TUBES.

Application filed October 21, 1920. Serial No. 418,360.

To all whom it may concern:

Be it known that I, MARK K. BOWMAN, a citizen of the United States, and resident of Montclair, in the county of Essex and State of New Jersey, have invented certain new and useful Improvements in Apparatus for Cleaning Boiler Tubes, of which the following is a specification.

My present invention is primarily concerned with apparatus of the projectile type for cleaning dirty boiler tubes or condensers, that is, with apparatus of the type to be driven through the dirty tube, preferably by the propulsive force of compressed air, although water or other liquid or gas may be used, the device having means for mechanically removing the mud or slime from condenser tubes or the accumulation of scale from the boiler or condenser tubes and driving the accumulation ahead of it as it is propelled through the tube. The apparatus of my present invention is broadly of the same type as that of my Patent No. 1,325,348, issued December 16, 1919 and of my copending application, Serial No. 397,574, filed July 20, 1920 and can be used in substantially the same relations as the devices of said patent and said application.

An object of the invention is to provide a tube cleaning projectile of the above type which shall be effective in its action and inexpensive in its construction and which shall be susceptible of being formed in any sizes for use with tubes of any diameter, and which shall be particularly useful in cleaning tubes of the very smallest diameters.

According to one feature of the invention, I employ identical generally rectangular spring metal plates to serve as scraper elements, each having an asymmetrically arranged polygonal aperture, all fitted over a rod of corresponding cross-section, the successive plates extending outwardly from the rod at relatively small angular intervals.

According to another preferred feature of the invention, round sided eyelets fitting over the rod are used as spacers between successive plates.

Referring now to the drawings in which

ments of the several features of the invention,

Fig. 1 is a side elevation of a preferred form of tube cleaning projectile,

Fig. 2 is a perspective view thereof, 55

Fig. 3 is an end elevation thereof taken

from the right end,

Fig. 4 is a detail view of the supporting rod and the nuts on the end thereof,

Fig. 5 is a plan view of the washer, 60

Fig. 6 is a plan view of a spacer member, and;

Fig. 7 is a view showing the respective angular positions of successive scraper plate elements. 65

Fig. 8 is a plan view of a modification.

The views are all shown on a scale substantially double that of the smallest projectile for actual use in order to better disclose the details of the construction. 70

Referring now to the drawings, I have shown a projectile comprising a supporting rod 1 preferably square in cross-section having threaded ends 2 and 3 as shown for a purpose to be set forth hereinafter. Upon the rod are mounted a plurality of the identical spring metal scraper elements best shown in Fig. 7 comprising each a plate 4 of spring metal having parallel sides 5 and 6 and scale attacking end edges in the form 80 of arcs of a circle of a diameter equal to the length of the plate. Centrally of each plate and preferably asymmetrically thereof, I provide a square opening 8 of the same size as the cross-section of the rod 1, the center 85 of said square being preferably exactly at the center of the element one pair of sides of the square being at an angle substantially of $22\frac{1}{2}^\circ$ with respect to the length or the parallel sides of the plate, and the other 90 pair at an angle of $67\frac{1}{2}^\circ$, that is, at angles whose ratio is 1 to 3. It will be understood that plates B and D are stamped in the same die as plates A and C, stampings B and D lying upon the obverse side as compared 95 with stampings A and C. It will be understood that the plates are successively fitted over the rod 1 in the cycle of positions A, B, C and D at equal angular intervals of 45° .

Any appropriate means may be employed 100

to space the scrapers equidistantly from each other lengthwise of the rod, so that the operative faces 7 of the successive plates will lie substantially upon a helix as best shown in Fig. 2. For this purpose I prefer to employ ordinary eyelets of the type shown in Fig. 6. The eyelet, it will be understood, consists of a thin tube of metal collapsed in a die so as to assume the form of a sheet metal ring as best shown in Fig. 6.

By preference, four of the plates are placed in contact with each other at one end of the rod as shown at 11 in the end view of Fig. 3, no spacers being interposed. These plates are angularly displaced with respect to each other, one corresponding to each of the positions indicated in Fig. 7 so that in end view, these plates produce substantially the disk effect shown in Fig. 3, although a single disk may be used, if desired. The same construction may be employed at the left-hand end of the device, although two contacting plates at right angles to each other, as shown in Fig. 1, are preferably employed. A circular leather washer 15 somewhat larger in diameter than the length of the scraper plates is fitted over the threaded end 2 of the rod, and a similar cork washer 18 is interposed between the set of plates at the end 3 and the plate adjacent thereto, and nuts 13 and 14 are threaded respectively over said ends to maintain the entire projectile in assembled relation, the nuts being preferably locked in position by means not shown.

In operation, more particularly for cleaning the slime out of condenser tubes, the projectile is forced a short distance into one of the tubes, the end of nut 13 in advance and compressed air or other propelling fluid is admitted to the tube. The force of the fluid as in the case of my prior patent and application will be sufficient to drive the device through even a dirty tube with high velocity. In this action, the leather washer which is in advance will push before it any loose mud or slime in the tube and the spring metal plates which are preferably of a length approximately equal to the diameter of the tube will effectively loosen any slime or mud or any accumulation of scale adhering to the walls. The mud, slime or scale is attacked by the edge 7 of the scraper plates, and since these edges are arranged at angular intervals about the rod, the entire interior surface of the tube will be cleaned. The cork washer 18 at the rear or trailing end of the projectile has a peculiar clinging effect with respect to the tube and effectively wipes the remaining mud or slime out of the tube, the air blast acting to remove any moisture remaining in the tube. Leather washers, it is found, have a tendency to allow mud or slime to slip by. The same construction of projectile may

be used in the same manner for cleaning boiler tubes, but I prefer in this case to omit the cork washer 18. In this event, as the advanced leather washer 15 emerges from the tube, the current of air being no longer confined in back of the same, will blow between the plates and the projectile will thus be delivered from the end of the tube at low speed.

If desired, the projectile may be used for cleaning boiler tubes, the end carrying the leather washer being at the rear or trailing end. In this operation the leather washer 15 which is of somewhat larger diameter than the tube will become cupped and will thus wipe the inner surface of the tube.

It will be seen that by my construction the scraper elements are directly secured to the central supporting rod by direct contact therewith, a firm hold against relative rotation being effected by reason of the non-circular cross-section of the rod and the correspondingly shaped apertures or holding edges in the scraper plates. It is, therefore, apparent that I can provide a projectile adapted for tubes of smaller diameter than would be possible in a case in which separate sleeves or other elements would be required to mount the scraper elements upon the supporting rod.

It will be seen that my present invention provides a construction which is particularly inexpensive in that the scraper elements are all made of identical spring metal stampings so that only one die and one operation is necessary to produce them and the spacers are formed by simply collapsing eyelets of appropriate size and of any ordinary or standard construction. The assembly of the device can be easily and quickly effected by unskilled labor and without the use of special tools.

In the preferred form of my invention, the plates are at angles of 45° with respect to each other, that is, at angles of one half the 90 degree angle subtended at the center of the square aperture 8 by each of the sides thereof. Similarly if a regular hexagonal rod were employed, the successive plates could be arranged at angles of 30 degrees with respect to each other, or one half of the 60 degree angle subtended at the center of the hexagonal aperture by one of the sides thereof. It will be apparent that the same general relation would hold in any case where a rod is employed having a regular polygonal cross-section, and where the correspondingly shaped aperture in each plate is disposed asymmetrically thereof, the sides of the aperture at the vertex thereof of adjacent the side of the plate being preferably at angles relative to the length of the plate having a ratio of 1 to 3, in the same manner as in the case of the square aperture as described above.

Thus, it will be seen that although only a single die need be used in making all of the plates, yet by providing the polygonal apertures in the plates in the asymmetrical position shown, the angle between successive plates will be less than the angle between successive sides of the polygonal rod. Therefore, there is an effective peripheral distribution of the scale attacking edges and 10 a projectile of short length will be adequate. Such short projectile can turn corners in the tubes to be cleaned with great facility.

Where two or more plates are angularly disposed in direct contact with respect to 15 each other intermediate the ends of the projectile, the construction obviously has not the flexibility inherent in the arrangement described, in which each pair of consecutive plates is separated by a spacer.

20 The eyelet spacers, it will be observed, will not rot or disintegrate in the presence of grease or oil, which the projectile may sometimes be called upon to remove. The spacers being metallic are relatively permanent and afford a resilient self-accommodating bearing surface for the plates that ease the shock, otherwise taken by the plates as they encounter obstructions in being projected through the tubes. The eyelets, moreover, have rounded edges to assure a gradual curvature of the operating plates as they encountered obstacles in passing through the tubes.

A desirable alternative form of scraper 35 element is shown in Fig. 8. This element is in the shape of a Greek cross as would result from superposing two of the plates of Fig. 7 at right angles to each other. The sides of the square opening 8' being at angles of 40 $22\frac{1}{2}^\circ$ and $67\frac{1}{2}^\circ$ with respect to the sides of the cross, it is apparent from the foregoing that the axes of each plate could be mounted to extend at angles of 45 degrees with respect to those of the preceding and the succeeding plates, the axes of alternate plates 45 being parallel to each other. By this construction, I provide double the scraping edge length for a given length of projectile as compared with the form of Fig. 7 and the 50 device is thereby rendered mechanically stronger and more effective in operation.

I claim:

1. A tube cleaning projectile of the class described, comprising in combination, a rod, 55 a plurality of scraper elements encircling said rod, said rod and elements being constructed and arranged to prevent rotation

of said elements about said rod, and spacer elements between successive scraper elements, each said spacer element comprising 60 a hollow annular metal member.

2. A tube cleaning projectile of the class described, comprising in combination, a rod having a non-circular cross-section, a plurality of scraper elements having holding eyes 65 snugly fitted about said rod to prevent rotation of said elements with respect to said rod and ring shaped members substantially circular in cross-section encircling said rod and serving to space said scraper elements 70 equidistantly from each other.

3. A tube cleaning projectile of the class described, comprising in combination, a rod, a plurality of identical scraper plates fixed thereon, to extend at equal angular intervals, 75 means spacing said plates equidistantly and a plurality of said plates fixed near one end of the projectile in direct contact with each other and at said angular intervals, to form a substantially disk-like structure.

4. A tube cleaning projectile of the class described, comprising in combination, a rod having a regular polygonal cross-section, a plurality of identical scraper plates having a width smaller than the length thereof, 80 each plate having an aperture at its center of the same size and shape as the cross-section of said rod, the sides of said aperture extending at an angle to the length of the plate, whereby said plates may be fitted over 85 said rod to extend outwardly therefrom at angular intervals in a number of directions equal to the number of sides of the polygon, spacers between successive plates, a number 90 of the plates at one end of the projectile being in contact with each other to form a 95 disk-like structure.

5. A tube cleaning projectile of the class described, comprising in combination, a rod having a regular polygonal cross-section, a 100 plurality of identical scraper plates having a width smaller than the length thereof, each plate having an aperture at its center of the same size and shape as the cross-section of said rod, the sides of said aperture being at angles relative to the length of the 105 plate, having a ratio of 1 to 3, whereby said plates may be fitted over said rod at equal angular intervals in a number of directions equal to the number of sides of the polygon. 110

Signed at New York, in the county of New York and State of New York, this 19th day of October, A. D. 1920.

MARK K. BOWMAN.
